UNITED STATES PATENT OFFICE.

FREDERICK CLEVELAND BASSICK, OF BRIDGEPORT, CONNECTICUT, ASSIGNOR TO THE BASSICK COMPANY, OF BRIDGEPORT, CONNECTICUT, A CORPORATION OF CONNECTICUT.

CABINET LATCH.

1,412,599.

Specification of Letters Patent. Patented Apr. 11, 1922.

Application filed April 7, 1921. Serial No. 459,395.

To all whom it may concern:

Be it known that I, FREDERICK C. BASSICK, a citizen of the United States, residing at the city of Bridgeport, Fairfield County, 5 Connecticut, have invented certain new and useful Improvements in Cabinet Latches; and I do declare the following to be a full, clear, and exact description of the invention, such as will enable others skilled in the art 10 to which it appertains to make and use the same.

This invention relates to certain new and useful improvements in gravity latches, and the primary object thereof is to provide a 15 structure wherein a bail or suitable handle is employed having one end extended to perform the function of a crank, the crank having connection with a pivoted latch member so as to operate the latter.

20 A further object of the invention is to provide a simple and economical latch which consists of a minimum number of parts i. e., a casing, a latching member and a handle, which can be easily assembled and which are 25 positive in operation.

The invention still further aims to provide a latch structure which can be easily operated and which is devoid of parts likely to become deranged or inoperative.

30 In the drawings:

Figure 1, is a rear elevation of the invention;

Figure 2 is a section on line 2—2 of Figure 1;

35 Figure 3 is a section on line 3—3 of Figure 1; and

Figure 4 is a detail perspective view of the handle member.

In proceeding in accordance with the present invention, a casing 1, is employed having an open back and having a front 2 and sides 3, the casing being secured in position by means of suitable fastening screws 4 or the like. Of course, a back plate may be 45 employed if desired.

To the rear face of the casing front a horizontal latching member 5 is disposed and offset at 6 at one end and pivoted to the front as indicated at 7 and has its opposite end 50 portion 8 extended through an elongated slot

9 provided therefor in the adjacent side 3 of the casing. The central portion of the latching member is formed with a depending arm 10 having an opening 11 therein.

The handle 12 is preferably of bail form 55 having its side arms 13 extending over the opposite sides of the casing and the free ends of the arms thereof bent inwardly at approximately right angles at 14 and journaled in openings 15 formed in the casing sides. 60 One of the arms has its end portion 14 extended and bent or disposed to project toward the casing front and to form a crank 16, which latter has its free end extending through the opening 11 in the arm 10 of the 65 latching member.

From the foregoing it will be seen that upon raising the bail-like handle, the crank of the latter will rock or swing the latching member about its pivot thereby raising the 70 free outer end of the latching member. Upon release of the handle, the latter will gravitate to down position carrying the latching member with it, though it will be obvious that the latching member will itself 75 also respond to the force or action of gravity, upon release of the handle member, and move downwardly, thus assuring a certain and positive operation of the device.

The offsetting of the pivoted end of the 80 latching member effects spacing of the arm 10 from the front of the casing, so as to provide ample room for the crank to operate in without binding against the casing front, so as to assure of the handle promptly responding to the action of gravity when released following movement thereof to raise the latching member.

The latching member 5 engages any suitable keeper 17. 90

What is claimed is:

1. In a gravity latch, a casing, a latching member offset at one end and pivoted to the casing and having its opposite end extending outwardly from a side of the casing, a central 95 apertured arm depending from the latching member, and a suitable handle having its ends turned inwardly and journaled in the casing sides and having one of said ends extending outwardly to form a crank which 100

latter projects through the aperture of the arm of the latching member to actuate the latter.

2. In a gravity latch, a casing, a latching member pivoted at one end in the casing and having its opposite end extending beyond the casing, an arm depending from the mem-

ber, and a suitable handle having the free ends thereof journaled in the casing and having one of the ends provided with means connected to the arm to actuate the member.

In testimony whereof I affix my signature hereto.

FREDERICK CLEVELAND BASSICK.
